ELECTRONIC SIREN

William Fleming, San Leandro, Calif., assignor to
Selectronics, Inc., San Leandro, Calif., a corporation of California

Application April 19, 1948, Serial No. 21,779

2 Claims. (Cl. 177—7)

1

The present invention relates to audible warning devices of the type known as sirens which are adapted to generate a penetrating sound of alternately rising and falling pitch and are generally employed on police cars, fire engines, ambulances, etc.

Sirens capable of producing a signal of the kind characterized employ usually rotating vanes that are arranged to direct a current of air against a pair of concentrically superposed perforated discs one of which is rotated at great speed so that the jets of air permitted to escape when the perforations of the two discs register, are interrupted and re-established in rapid succession and thus produce a sound of a pitch determined by the speed of rotation. While the movable elements of the described structure may be driven manually, sirens employed on automotive vehicles of the type referred to are usually provided with electric motors which are energized from the batteries of said vehicles.

The operation of these motors constitutes a very heavy drain on the power stored in the batteries due to the weight of the rotary disc, which should be heavy to develop momentum, and due to the resistance of the sound producing air jets which the rotary disc must cut in continuous succession; and this drain on the power of the batteries is especially objectionable in vehicles of the type named above where the same battery may have to sustain powerful signalling lights, public address systems, radio transmitting sets and the like.

It is an object of the present invention to furnish an electrically operated audible warning device, adapted to produce the characteristic sound of a siren, which requires a minimum of electric power to start or maintain operation.

It is another object of the present invention to furnish an audible warning device, of the type referred to, which is adapted to produce the characteristic sound of a siren without requiring manual actuation or motor power for operation.

Furthermore it is an object of the present invention to furnish an electrically operated audible warning device, of the type referred to, which involves no mechanical movement other than the vibrations of a sound producing membrane.

Additionally it is an object of the present invention to provide an arrangement that may selectively be used as a siren or as a public address system.

These and other objects of my invention will be apparent from the following description of the

2

accompanying drawing which illustrates a preferred embodiment thereof and wherein

Figure 1 is the circuit diagram of an electrically operated sound-producing device constructed in accordance with my invention,

Figure 2 is a circuit diagram illustrating part of the system shown in Figure 1 with the symbols of its components re-arranged to facilitate an understanding of their functions, and

Figure 3 is a graph representing the performance of the arrangement illustrated in Figure 2.

In accordance with my invention I provide an audio-oscillator with means automatically effective to vary the frequency of the generated oscillations and apply its varying output, with or without amplification, to a suitable loudspeaker. When such a system is energized, it produces signals that closely resemble the sound produced by the conventional acousto-mechanical sirens, but

consumes far less electrical power than the motors required to operate acousto-mechanical sirens and involves no mechanical movement other than the vibrations of the loudspeaker membrane.

Having reference to the accompanying drawings, the arrangement of my invention illustrated in Figure 1 comprises an audio-oscillator O arranged to feed into an audio-amplifier A—A which amplifies the oscillator output and delivers it in amplified form to a loudspeaker circuit L.

As more clearly shown in Figure 2, the audio oscillator O comprises a source of D. C. voltage 10, a resistor 11, a relatively large condenser 12 and a control switch 13 connected in series; and shunted across said condenser 12 is a large resistor 14 in series with a relatively small condenser 15 that is by-passed by a discharge tube 16 filled with an inert gas, such as neon. Tubes of this type are practically non-conductive until

a sufficient voltage is placed across their electrodes to ionize the gas, said voltage being termed the firing or ionization voltage. Thereafter the tubes remain conductive until the applied voltage drops below a critical value which is generally substantially lower than the firing voltage and which is termed the extinction or deionization voltage.

When the switch 13 is closed, both the condensers 12 and 15 are effectively connected across the source of voltage 10, and both condensers begin to charge; and depending upon the firing characteristics of the tube 16, the size of resistors 11 and 14 and the capacity of condenser 15, the voltage building up in said condenser 15 will quickly reach a value adequate to ionize the

tube 16 which thus becomes conductive and causes condenser 15 to discharge. However, as soon as the voltage stored in said condenser drops below the extinction point of the tube 16, said tube returns to non-conductive condition permitting condenser 15 to re-charge until its voltage reaches again the firing point of the tube 16 whereupon another cycle of discharge followed by recharging will occur. Thus, as long as the switch 13 remains closed the condenser will continue to alternately discharge to the level set by the extinction point of tube 16 and re-charge to the level set by the firing point of said tube.

Reverting to the large condenser 12, said condenser is of such size relative to the voltage applied thereto through resistor 11 as to require, for charging to full capacity, a period of time which extends over a predetermined multiple of the cyclic voltage variations occasioned in condenser 15 by the presence of the neon tube 16. Hence, during the initial stages in the operation of the described system while the condenser 15 discharges and re-charges alternately in the manner explained above, the voltage in the large condenser 12 increases steadily and due to this increase in the charge of said condenser the recharging time of condenser 15 becomes progressively shorter with every successive cycle until the condenser 12 is fully charged. At this point then the frequency of the discharges of condenser 15 has reached its maximum and from there on remains constant at said maximum as long as the switch 13 stays closed.

As indicated, the time that will elapse before the frequency of the discharges produced by the described system reaches its maximum value depends primarily upon the charging time of the condenser 12, which in turn is determined by the capacity of said condenser and by the size of the timing resistor 11, an increase in either being instrumental in prolonging the charging time of condenser 12. Therefore, to control the rate at which the frequency of the oscillations generated in the described manner reaches its maximum, either the condenser 12 or the timing resistor 11 or both may be variable as diagrammatically indicated in Figure 2.

The frequency to which the oscillations generated by the system of my invention will rise, is determined not only by the characteristics of the neon tube 16 but also by the capacity of the relaxation condenser 15 and by the value of the voltage limiting resistor 14, a decrease in either of the latter components being instrumental in raising the upper frequency limit to higher levels; therefore, to control said upper frequency limit the resistor 14 may be variable as indicated in Figure 2.

Whenever the switch 13 is opened to interrupt the supply of power, while the described arrangement is in full operation, the energy stored in the large condenser 12 will continue to charge and re-charge the relaxation condenser 15 for some time but the time required to re-charge said condenser to the firing point of its associated neon tube 16 will increase with every successive cycle due to the successive decrease of the energy stored in condenser 12, until the voltage available in the storage condenser is no longer able to charge the relaxation condenser 15 to the firing point of the tube 16 and the oscillations to an end. Thus, whenever the switch 13 is opened after the described arrangement has been in operation for some time, said arrangement will produce oscillations of a decreasing frequency

for a period of time primarily determined by the capacity of condenser 12 relative to condenser 15, an increase in the latter or a decrease in the former being instrumental in shortening the "die-down" period of the oscillations. To reduce this "die-down" period without at the same time shortening the period over which the frequency of the generated oscillations builds up when the arrangement of my invention is set into operation, a bleeder resistor 18 may be shunted across the storage condenser 12, as shown in Figures 1 and 2, and to abruptly terminate the performance of the described system during the "die-down" period, a normally open manually operable shunt switch 19 may be connected across the plates of the condenser 12, as shown, in order that said condenser may be instantaneously discharged, if desired.

Reverting to Figure 1, the oscillations generated in the described relaxation arrangement O are supplied through a suitable blocking condenser 20 and an isolation resistor 21 to the control grid 22 of an audio amplifier tube 23 which forms the first stage of the previously mentioned audio-amplifier A—A. The anode circuit of tube 23 is coupled through an iron-cored transformer 24 to a push-pull circuit 25 comprising a pair of tubes 26 and 27 respectively which have their control grids connected to opposite ends of the secondary winding of the coupling transformer 24 while their plates are connected to opposite ends of the primary winding of another coupling transformer 28, the secondary winding of which forms part of the loudspeaker circuit L being connected across a suitable loudspeaker 29 as shown.

Thus, whenever the switch 13 of the relaxation oscillator O is closed, the electrical oscillations generated by the discharges of the condenser 15 through the neon tube 16 are amplified in the audio amplifier A—A and are supplied in appropriately amplified form to the circuit L to be converted into audible signals in the loudspeaker 29 where they produce a penetrating sound of a rising pitch that finally adjusts itself to an upper frequency determined by the constants of the relaxation arrangement O as previously described; additionally, due to the filter network formed by the coupling condenser 20 in combination with the isolation resistor 21 between the oscillator arrangement O and the audio amplifier A—A the volume of the signal emitted by the loudspeaker will increase with increasing frequency. On the other hand whenever the switch 13 is opened, the sound emitted from the loudspeaker 29 will gradually decrease in pitch and volume and will finally terminate unless the switch is closed again. Thus, the system of my invention is able to produce a penetrating sound of the characteristic wail of an acousto-mechanical siren, without requiring any mechanical motion other than the vibration of a loudspeaker membrane, merely by energization of electronic circuits which require far less power than the motors necessary to operate the heavy armatures of the conventional acousto-mechanical sirens. In addition my invention provides a very substantial saving in equipment in all instances where it is desirable to have both a siren and a public address system available such as at air ports, on police cars, fire engines and the like, because a microphone circuit M may readily be connected to the amplifier A—A of the device of my invention. Such an arrangement is illustrated in Figure 1 wherein

an input transformer 30 delivers the voice modulations impressed by a microphone 31 upon a D. C. current supplied by a battery 32 through a suitable volume control potentiometer 33 to the control grid 22 of the previously described audio amplifier tube 23. Hence any address or warning spoken into the microphone 31 is amplified in the audio amplifier A—A and delivered to the public in properly amplified form through the same loudspeaker 29 that emits the siren signals whenever the switch 13 of the relaxation oscillator O is manipulated.

As an added advantage my invention permits pre-adjustment of sirens of identical construction to signals of distinctly different character depending upon the purpose for which they may be used. By pre-setting the timing resistor 11 and/or the storage condenser 12, it is possible to shorten or extend the build-up period of the signal at will, and by adjusting the voltage-limiting resistor 14 the frequency to which the signal will rise may be predetermined to give it a distinctly high or low characteristic; furthermore by adjustment of the bleeder resistor 18 the "die-down" period of the signal may be shortened or extended so that it will end abruptly or roll on for some time. Thus, by combining selected ones of these alternatives the sirens of my invention may be given an one of a wide range of distinct sound characteristics that may identify their place of origin as an ambulance, a police car, a fire engine, or whatever other purpose they may serve.

In a practical embodiment of my invention constructed according to the diagram shown in Figure 2, I employed components having the following constants:

Resistor 11, 200,000 ohms.

Resistor 14, 15 megohms.

Resistor 18, 5 megohms.

Resistor 21, 500,000 ohms.

Condenser 12, 4 microfarads.

Condenser 15, 500 micromicrofarads.

Condenser 20, 500 micromicrofarads.

Neon tube 16:

Ionization voltage, 75 volts.

Deionization voltage, 65 volts.

Source of power 10, 250 volts plus.

Figure 3 illustrates the rate of increase in the frequency of the generated oscillations obtained in a device employing the above stated circuit constants and indicates that the system commenced to oscillate in less than 1 second after the switch 13 was closed, but required more than four seconds thereafter before the frequency climbed to its constant maximum value of 600 cycles per second. Comparative tests showed that it required less than 50 watts to set the system of my invention into operation whereas more than 1200 watts are frequently required to start operation of conventional acousto-mechanical sirens.

While I have explained my invention with the aid of a specific embodiment thereof, I do not wish to be limited to the particular circuit arrangement shown in the drawing of the ex-

emplary data stated in the specification, both of which may be departed from without departing from the scope and spirit of my invention. Thus, although I have described and illustrated a particular audio amplifier, it will be understood that other audio amplifiers may be successfully employed in the system of my invention. Also, while I have disclosed a particular audio oscillator as forming an essential part of my novel siren, the man skilled in the art, once acquainted with the principles of my invention, will be able to adapt other oscillators for operation within the system of my invention by arranging them in accordance with my invention in such a manner that the frequency of their oscillations will vary automatically in a predetermined pattern.

Having thus described my invention and the manner in which it is to be performed, what I claim is:

- 20 1. An electronic siren including in combination an audio oscillator comprising a first resistor, a first capacitor and a control switch in series, a second resistor and a second capacitor in series connected across said first capacitor, said second capacitor being of a smaller value than said first capacitor, a gas discharge tube shunted directly across said second capacitor and a bleeder resistor and a shunt switch each connected individually across said first capacitor; an audio amplifier arranged to amplify the oscillations generated by said oscillator, and a loudspeaker arranged to reproduce the output of said amplifier.
- 25 2. An electronic siren including in combination an audio oscillator comprising a first resistor, a first capacitor and a control switch in series, a second resistor and a second capacitor in series connected across said first capacitor, said second capacitor being of a smaller value than said first capacitor, and a gas discharge
- 30 3. An electronic siren including in combination an audio oscillator comprising a first resistor, a first capacitor and a control switch in series, a second resistor and a second capacitor in series connected across said first capacitor, said second capacitor being of a smaller value than said first capacitor, and a gas discharge
- 35 4. An electronic siren including in combination an audio oscillator comprising a first resistor, a first capacitor and a control switch in series, a second resistor and a second capacitor in series connected across said first capacitor, said second capacitor being of a smaller value than said first capacitor, and a gas discharge
- 40 5. An electronic siren including in combination an audio oscillator comprising a first resistor, a first capacitor and a control switch in series, a second resistor and a second capacitor in series connected across said first capacitor, said second capacitor being of a smaller value than said first capacitor, and a gas discharge
- 45 6. An electronic siren including in combination an audio oscillator comprising a first resistor, a first capacitor and a control switch in series, a second resistor and a second capacitor in series connected across said first capacitor, said second capacitor being of a smaller value than said first capacitor, and a gas discharge
